AUTOMATIC TIME SWITCH

Herbert W. Daggs, Cleveland, Ohio

Application January 13, 1938, Serial No. 184,819

15 Claims. (Cl. 200—38)

This invention relates to improvements in automatic time switches adapted to actuate switches at predetermined times.

An object of my invention is to provide an automatic time switch, which possesses a high degree of flexibility, and is thus adapted to combine a single switch device pole, double pole, two circuit or other features.

Other objects are, to provide a time switch, which can be built at a relatively low cost, the same being positive, accurate and precise in action, and adapted to be used within a relatively wide range of uses.

Still other objects are to provide a device of the type described, which may be quickly and easily regulated to operate at a predetermined time, the same being adapted to be encased in a relatively small container where it may be readily accessible.

Other objects and advantages of the invention will be apparent during the course of the following description:

In the drawings accompanying this specification:

Fig. 1 is a front elevational view of my new and improved time switch showing it mounted in a box,

Fig. 2 is a side elevational view,

Fig. 3 is a sectional view taken on the line 3—3 of Fig. 2 showing the retaining spring,

Fig. 4 is a sectional view taken on the line 4—4 of Fig. 1, showing the mercury switch,

Fig. 5 is a sectional view taken on the line 5—5 of Fig. 2,

Fig. 6 is a diagrammatic view taken on the line 6—6 of Fig. 2, showing the rocker carriage and parts associated with it for actuating it,

Fig. 7 is a view corresponding to Fig. 6 showing the position of the parts just before the rocker carriage is tripped, and

Fig. 8 corresponds to Fig. 6 and shows the rocker carriage in another position.

Conventional time switches are commonly divided by the trade into various distinct types, conventionally designated, for example, as "type A," which provides for turning on circuits Nos. 1 and 2 separately and turning them off simultaneously. "Type B," for simultaneously turning on circuits Nos. 1 and 2 and turning off No. 1 and then all off. "Type C" for turning on circuit No. 1, then No. 2 and turning off No. 1 and then all off. Likewise types "D," "E," "F" and "G" provide various modifications of the sequence of switch operation above described. Each of the various types of switches is adapted to be utilized

for certain particular types of work. For example "type A" may be particularly adapted for actuating store display switches, while "type B" may be adapted for actuating electric light switches in apartment houses, where No. 1 circuit may control hall lights and No. 2 may control the lights in front of the apartment.

While each of the foregoing switches is adapted to perform its work in the particular place where it operates, it is not adapted to be regulated to be operated as any of the other switch types. I have discovered that a single time switch device may be provided, having such a wide range of flexibility, that it is adapted to be readily regulated to perform the actuation of switches in the manner of any of the foregoing types, furthermore I have discovered means for accomplishing such results by new and novel means.

In the drawings the numeral 11 represents a box, encasing my device, adapted to be supported on a wall in a vertical position and conveniently provided with a swinging door, adapted to be locked. A frame 12, providing a supporting means for the mechanism hereinafter described, 20 secured to the box 11 by means of screws 13, provides for the ready removal of the device from the box 11. A mounting plate 14, positioned on the plane of the frame 12 is secured thereto by means of braces 15 anchored by screws 16, while 25 a motor support plate 17 is mounted in spaced relation to the mounting plate 14 by the cooperation of internally threaded tubes 18, secured to the braces 15 and the mounting plate 14 by a 30 pressed fit, and receives screws 19 providing 35 means for quickly and easily removing the motor support plate 17 from the frame 12.

Lifting arms 20a and 20b adapted to be moved vertically upwardly and downwardly are provided with upper slots 21a and 21b, serving to guide said lifting arms 20a and 20b along an upper hollow guide post 22, secured to the upper part of the frame 12 by screw 23 and nut 24, while intermediate slots 25a and 25b permit said lifting arms to be slid along an hour wheel shaft 26 in 45 a similar manner. Likewise lower slots 27a and 27b near the lower ends of lifting arms 20a and 20b permit said arms to be slid along a relatively long lower guide post 28, provided with spacing washers 29 and threaded interiorly receiving 50 screws 30. Horizontally disposed slots, slightly larger than the top of the lifting arms 20a and 20b, positioned in a lifting arm guard 31 fixedly mounted at the top of the frame 12 and extending 55 forwardly therefrom, provide additional 55

guide means for lifting arms 29a and 29b, while a guard 32 serves to protect the moving parts, and acts as a pointer for telling time.

Change weight members 33a and 33b are pivotally mounted respectively on the lifting arms 29a and 29b by means of pins 34a and 34b, while change weight studs 35a and 35b, cooperating with respectively change weight members 33a and 33b as hereinafter described, are secured to rocker carriages 36a and 36b, which are pivotally mounted on lower guide post 28. Retaining springs 37a and 37b, as shown in Figs. 2 and 3 are provided for maintaining the rocker carriages in position against the dragging action of other parts. Mercury switches 38a and 38b, are mounted horizontally on the rocker carriages 36a and 36b by means of clamps 39a and 39b respectively, and are of such design and construction that they are in a circuit completing condition when the large ends thereof are tilted downwardly, as shown in Fig. 1 and are in non-circuit completing condition when the large ends are tilted upwardly. Wires 40a and 40b connect rocker carriages 36a and 36b respectively to conventional terminals 41a and 41b mounted on terminal block 42 from which appropriate wires lead to the various circuits controlled by this time switch. Coiled tension springs 43a and 43b, secured to the lower ends of the lifting arms 29a and 29b, are retained by spring post 44, and serve to effectively draw downwardly the lifting arms and thus serve to give impetus to the downward movement in an obvious manner.

The timing of the device herein described is accomplished by means of timing dials 45a and 45b, fixedly mounted on the hour wheel shaft 26, and provided around their peripheries by apertures 46a and 46b beneath which numerals corresponding to the time according to hours, or fractions thereof may be provided. One half of the timing dials 45a and 45b may be appropriately designed to represent the day hours and the other half the night hours. Cam hands 47a and 47b loosely pivotally mounted on the hour wheel shaft 26 are provided with setting pins 48a and 48b adapted to be selectively set in any of time indicating apertures 46a and 46b respectively. The ends of the cam hands 47a and 47b are provided with curved cam surfaces 49a and 49b adapted to operate lifting lugs 50a and 50b for actuating lifting arms 29a and 29b respectively.

Actuating means comprise an electric motor 51, secured to motor support plate 17 by means of screws 52 which drives the hour wheel shaft 26 in an obvious manner through the cooperation of third wheel 53, pinion 54, center wheel 55, intermediate gear 56 and hour wheel 57, while a setting stem 58 adapted to receive a winding key, not shown, has a setting pinion 59 cooperating with intermediate gear 56 to permit the timing dials 45a and 45b to be rotated in setting the device. The motor 51 is adapted to be driven in cooperation with the above described driving means in such manner that the dials 45a and 45b make one complete revolution each 24 hours.

In using the device herein described, the operation of only the front timing dial 45a and associated parts will be described, as it will be understood that timing dial 45b is operated in the same manner. The operator draws the cam hands 47a outwardly to pull out setting pin 48a and then moves a hand 47a around to the aperture 46a corresponding to the time designated thereon, at which he desires the mercury switch 38a to close the circuit, and then in a corresponding manner

sets the other cam hand 47a at the time designated on the timing dial 45a when he desires the mercury switch 38a to break the circuit. Assuming that the motor 51 and associated driving parts rotates the dial 45a in a clockwise manner, as viewed in Fig. 1, and that switch 38a is in a circuit breaking position, no movement of lifting arm 29a will occur until the curved cam surface 49a of cam hand 47a contacts the lifting lug 50a, mounted on the lifting arm 29a, and raises the lifting lug 50a.

At that time change weight member 33a will also be lifted upwardly, and as the continued rotation of cam hand carries it beyond the lower end of lifting lug 50a, the lifting arm 29a, will drop down due to the pull of gravity thereon, and also the action of spring 43a. The result of this movement is that the weight of the falling lifting arm 29a will cause change weight member 33a to drop onto the left of the two change weight studs 35a, as viewed in Fig. 1, resulting in the tilting of rocker carriage 36a into the position illustrated in Fig. 1, and the mercury in the switch 38a closes the circuit, which remains in a closed position until the other cam hand 47a, by continued rotation of the timing dial 45a contacts the lifting lug 50a, which again will be carried upwardly as herein described.

When the lifting lug 50a rides over the end of the succeeding cam hand 47a the downwardly movement of the lifting arm 29a, as above described, will cause change of weight member 33a to contact the right hand change of weight stud 35a, and this action tilts the pivotally mounted rocker carriage in the opposite direction. Obviously the circuit through the switch 38a will be broken, and will remain in such condition until the lifting arm 36a is again lifted up by one of the cam hands 47a set at a predetermined hour.

The timing dial 45b and associated parts are set, actuated and operated in exactly the same manner as are the corresponding parts of dial 45a and associated parts. A convenient winding key may be used to rotate the setting stem 58 in order to rotate the dials 45a and 45b when setting the device. The operation of the lifting arms 29a and 29b is clearly shown in Figs. 6, 7 and 8.

The time switch herein disclosed is adapted to be used in various types of work due to its high degree of flexibility and includes installation in connection with sign board displays, building lights, machinery hookups and the like.

It will be apparent to those skilled in the art, that the invention herein disclosed may be variously changed, used or modified, without departing from the spirit of the invention or sacrificing the advantages thereof, and that the embodiment of my invention is illustrative only and that my invention is not limited thereto.

I claim:

1. An automatic time switch device of the class described, comprising mercury switch means adapted to be moved into a circuit-opening position or a circuit-closing position, a rotatable timing dial having time indicating indicia mounted thereon, driving means for rotating said dial, setting means associated with said dial and adapted to be selectively set at any desired indicia on said dial, a reciprocable arm activated by said setting means, and means associated with said arm and said switch means, a trip mechanism pivotally mounted on said arm, positioned and arranged in such manner that in response to successive reciprocating movements of said arm

caused by said setting means it alternately tilts said switch means to circuit-opening and circuit-closing positions, whereby a circuit is alternately opened and closed in response to the actuation 5 of the setting means at predetermined times.

2. An automatic time switch device, comprising time indicating means provided with a series of spaced apertures, setting means disposed on said indicating means and provided with setting pins 10 adapted to be inserted in said apertures, said setting means being positioned and arranged on said indicating means in such manner that the setting means may be moved slightly away from the time indicating means to disengage said pins from said means and then moved around on said means to a desired point and locked thereon by the engagement of a setting pin with an aperture in said indicating means, a switch means, and means associated with said setting means and 15 said switch means for actuating said switch means at predetermined intervals regulated by the position 20 of the setting means on the time indicating means.

3. An automatic time switch device, comprising 25 a flat circular rotatable dial, provided with a series of spaced apertures disposed along the periphery thereof, radially disposed setting means disposed on said dial and provided with setting pins adapted to be inserted in said apertures, said setting means being positioned and arranged on said dial in such manner that the setting means may be moved slightly away from the time dial to disengage said pins from said dial and then moved around on said dial to a desired point and locked 30 thereon by the engagement of a setting pin with an aperture in said dial, a switch means, and means associated with said setting means and said switch means for causing said switch means to be actuated at predetermined intervals 35 regulated by the position of the setting means on the dial.

4. An automatic time switch device, comprising a rotatable time indicating means, provided with time indicating indicia and a series of spaced 40 apertures, positioned in cooperative relation to said indicia, radially disposed setting means disposed on said indicating means and provided with setting pins adapted to be inserted in said apertures, said setting means being positioned and 45 arranged on said indicating means in such manner that the setting means may be moved slightly away from the time indicating means to disengage said pins from said means and then moved around on said means to a desired point and locked 50 thereon by the engagement of a setting pin with an aperture in said indicating means, a switch means, and means associated with said setting means and said switch means for causing said switch means to be alternately actuated to 55 circuit opening and circuit closing positions at predetermined intervals regulated by the position 60 of the setting means on the time indicating means.

5. An automatic time switch device, comprising 65 a flat circular rotatable dial, provided with time indicating indicia and a series of spaced apertures, disposed along the periphery thereof and positioned in cooperative relation to said indicia, radially disposed setting means disposed 70 on said dial and provided with setting pins adapted to be inserted in said apertures, said setting means being positioned and arranged on said dial in such manner that the setting means may be moved slightly away from the time dial to disengage 75 said pins from said dial and then moved

around on said dial to a desired point and locked thereon by the engagement of a setting pin with an aperture in said dial, a switch means, and means associated with said setting means and said switch means for causing said switch means to be alternately actuated to circuit opening and circuit closing positions at predetermined intervals regulated by the position of the setting means on the dial. 5

6. An automatic time switch, comprising a carriage mounted on a horizontal pivot in such manner as to permit it to be alternately tilted from one side to the other, a switch means mounted in said carriage and positioned and arranged in such manner as to be alternately moved to circuit-opening and circuit-closing positions in response to the tilting movement of said carriage, a vertically disposed lifting member, means for lifting said member at predetermined times, and a change weight 10 member associated with said lifting member and positioned and arranged in relation to said carriage in such manner that it normally retains said carriage in one of its tilted positions but upon upward movement of the lifting member 15 it disengages from contact with the carriage and upon downward movement of the lifting member shifts the carriage to its opposite tilted position, whereby the switch means alternately opens and closes a circuit at predetermined times for 20 the purposes set forth. 25

7. An automatic time switch, comprising a carriage mounted on a horizontal pivot in such manner as to permit it to be alternately tilted from one side to the other, a mercury switch mounted 30 in said carriage and positioned and arranged in such manner as to be alternately moved to circuit-opening and circuit-closing positions in response to the tilting movement of said carriage, a vertically disposed lifting member, means for lifting 35 said lifting member at predetermined times, and a change weight member associated with said lifting member and positioned and arranged in relation to said carriage in such manner that it normally retains said carriage in one of its tilted 40 positions but upon upward movement of the lifting member it disengages from contact with the carriage and upon downward movement of the lifting member shifts the carriage to its opposite tilted position, whereby said switch alternately 45 opens and closes a circuit at predetermined times for the purposes set forth. 50

8. An automatic time switch, comprising a carriage mounted on a horizontal pivot in such manner as to permit it to be alternately tilted from one side to the other, a switch means mounted 55 in said carriage and positioned and arranged in such manner as to be alternately moved to circuit-opening and circuit-closing positions in response to the tilting movement of said carriage, a vertically disposed lifting member, means for lifting 60 said lifting member at predetermined times, and a change weight member pivotally mounted and depending from the lower end of said lifting member, the same being positioned 65 and arranged in relation to said carriage in such manner that it normally retains said carriage in one of its tilted positions but upon upward movement of the lifting member it becomes disengaged from contact with the carriage and upon downward movement of the lifting member shifts the carriage to its opposite tilted position, whereby the switch means alternately opens and closes 70 a circuit at predetermined times for the purposes set forth. 75

9. An automatic time switch, comprising a carriage mounted on a horizontal pivot in such manner as to permit it to be alternately tilted from one side to the other, a switch means mounted in said carriage and positioned and arranged in such manner as to be alternately moved to circuit-opening and circuit-closing positions in response to the tilting movement of said carriage, a vertically disposed lifting member, a movable time indicating device, driving means for actuating said indicating device, setting means adapted to be selectively set at a predetermined point on the time indicating device for lifting said lifting member at predetermined times, and a change weight member associated with said lifting member and positioned and arranged in relation to said carriage in such manner that it normally retains said carriage in one of its tilted positions but upon upward movement of the lifting member by said setting means it disengages from contact with the carriage and upon downward movement of the lifting member shifts the carriage to its opposite tilted position, whereby the switch means alternately opens and closes a circuit at predetermined times for the purposes set forth.

10. An automatic time switch, comprising a carriage mounted on a horizontal pivot in such manner as to permit it to be alternately tilted from one side to the other, a switch means mounted in said carriage and positioned and arranged in such manner as to be alternately moved to circuit-opening and circuit-closing positions in response to the tilting movement of said carriage, a vertically disposed lifting member, a follower means on said lifting arm, a movable timing dial, driving means for rotating said dial, setting means adapted to be selectively set at a predetermined point on said dial, the same being constructed and arranged to lift said follower means on said lifting member at predetermined times, and a change weight member associated with said lifting member and positioned and arranged in relation to said carriage in such manner that it normally retains said carriage in one of its tilted positions but upon upward movement of the lifting member by said setting means it disengages from contact with the carriage and upon downward movement of the lifting member shifts the carriage to its opposite tilted position, whereby the switch means alternately opens and closes a circuit at predetermined times for the purposes set forth.

11. An automatic time switch for controlling a plurality of switches from a single actuating device, comprising a plurality of carriages mounted on horizontal pivots in such manner as to permit them to be alternately tilted from one side to the other, a switch means mounted in each of said carriages and positioned and arranged in such manner as to be alternately moved to circuit-opening and circuit-closing positions in response to the tilting movement of its cooperating carriage, a vertically disposed lifting member for each carriage, means for independently lifting each lifting member at predetermined times, said means being actuated by a common driving means, and a change weight member associated with each lifting member and positioned and arranged in relation to its cooperating carriage in such manner that it normally retains its carriage in one of its tilted positions but upon upward movement of its cooperating lifting member it disengages from contact with the carriage and upon downward movement of the lifting member shifts the carriage

to its opposite tilted position, whereby a plurality of switch members alternately open and close circuits at predetermined times for the purposes set forth.

12. An automatic time switch, comprising a carriage mounted on a pivot in such manner as to permit it to be alternately tilted from one side to the other, a switch means mounted in said carriage and positioned and arranged in such manner as to be alternately moved to circuit-opening and circuit-closing positions in response to the tilting movement of said carriage, a vertically disposed lifting member, a movable time indicating device, driving means for actuating said device, setting means adapted to be selectively set at a predetermined point on said indicating device for lifting said lifting member at predetermined times, said setting means comprising an elongated member having a curved surface along its forward side adapted to engage said lifting member, and a change weight member associated with said lifting member and positioned and arranged in relation to said carriage in such manner that it normally retains said carriage in one of its tilted positions, but upon upward movement of the lifting member as it is carried upwardly on the curved surface of the setting member it disengages from contact with said carriage and upon downward movement of the lifting member shifts its carriage to its opposite tilted position, whereby the switch means alternately opens and closes the circuit at predetermined times, for the purposes described.

13. An automatic time switch, comprising a carriage mounted on a pivot in such manner as to permit it to be alternately tilted from one side to the other, a switch means mounted in said carriage and positioned and arranged in such manner as to be alternately moved to circuit-opening and circuit-closing positions in response to the tilting movement of said carriage on said pivot, a vertically disposed lifting member, means for lifting said member at predetermined times, means for facilitating the return of said lifting member to its normal position after it is lifted and a change weight member associated with said lifting member and positioned and arranged in relation to said carriage in such manner that it normally retains said carriage in one of its tilted positions but upon upward movement of the lifting member it disengages from contact with the carriage and upon downward movement of the lifting member shifts the carriage to its opposite tilted position, whereby the switch means alternately opens and closes a circuit at predetermined times for the purposes set forth.

14. An automatic time switch, comprising a carriage mounted on a pivot in such manner as to permit it to be alternately tilted from one side to the other, a switch means mounted in said carriage and positioned and arranged in such manner as to be alternately moved to circuit-opening and circuit-closing positions in response to the tilting movement of said carriage on said pivot, a vertically disposed lifting member, means for lifting said member at predetermined times, a coil spring secured to the framework supporting this device and connected to the lower end of said lifting device for facilitating the return of said lifting member to its normal position after it is lifted, and a change weight member associated with said lifting member and positioned and arranged in relation to said carriage in such manner that it normally

5 retains said carriage in one of its tilted positions but upon upward movement of the lifting member it disengages from contact with the carriage and upon downward movement of the lifting member shifts the carriage to its opposite tilted position, whereby the switch means alternately opens and closes a circuit at predetermined times for the purposes set forth.

10 15 An automatic time switch, comprising a carriage mounted on a horizontal pivot in such manner as to permit it to be alternately tilted from one side to the other, means for maintaining said carriage in position against the dragging action of other parts, a switch means mounted in said carriage and positioned and arranged in such manner as to be alternately moved to circuit-opening and circuit-closing positions in

response to the tilting movement of said carriage on said pivot, a vertically disposed lifting member, means for lifting said member at predetermined times, and a change weight member associated with said lifting member and positioned and arranged in relation to said carriage in such manner that it normally retains said carriage in one of its tilted positions but upon upward movement of the lifting member it disengages from contact with the carriage and upon downward movement of the lifting member shifts the carriage to its opposite tilted position, whereby the switch means alternately opens and closes a circuit at predetermined times for the purposes set forth.

15 HERBERT W. DAGGS.
